UNITED STATES PATENT OFFICE.

SOLOMON S. HOMES, OF SPRING HILL, IOWA.

DESIGN FOR A SNAP-HOOK.

SPECIFICATION forming part of Design No. 33,496, dated November 6, 1900.

Application filed October 9, 1900. Serial No. 32,555. Term of patent 7 years.

To all whom it may concern:

Be it known that I, SOLOMON S. HOMES, a citizen of the United States, residing at Spring Hill, in the county of Warren and State of Iowa, have invented a new and useful Design for Snap-Hooks, of which the following is a specification, reference being had to the accompanying drawings, forming a part thereof.

Figure 1 shows the complete design in perspective. Fig. 2 shows a side elevation of same, and Fig. 3 shows a similar view taken from a position at right angles to that from which Fig. 2 is taken.

The essential features of my design consist of a single elongated loop 10, made of wire that is round in cross-section. Projecting from the central portion of one side of this loop is a second loop 11 in a plane substantially at right angles to that of the loop 10 and tapering outwardly from a narrow point at its intersection with the loop 10. The sides of said loop are substantially straight, and the extreme outer end of the loop is rounded at 12. In each of the straight sides of the

loop 11 is an outwardly-inclined kink 13 of 25 semicircular contour. The end portions of the wire are extended parallel with the sides of the loop and are provided with outwardly-bent portions at 14, said portions entering the kinks 13. At the rounded end portion 30 12 of the loop 11 the two portions of the loop are flared or curved outwardly from each other at 15, as clearly shown in Fig. 3, and at the intersection of the loops 10 and 11 a half-turn is made in each wire at 16. 35

Having thus described my invention, what I claim as new, and desire to secure by Letters Patent, is—

The design for a snap-hook, substantially as herein shown and described. 40

In testimony whereof I have signed my name to this specification in the presence of two subscribing witnesses.

SOLOMON S. HOMES.
